UNITED STATES PATENT OFFICE.

JOSEPH H. ROACH, OF BROOKLINE, PENNSYLVANIA.

LATERALLY-MOVABLE TUYÈRE.

Application filed January 27, 1920. Serial No. 354,383.

To all whom it may concern:

Be it known that I, JOSEPH H. ROACH, a citizen of the United States, residing at Brookline, in the county of Delaware and 5 State of Pennsylvania, have invented certain new and useful Improvements in Laterally-Movable Tuyères, of which the following is a specification.

This invention relates to laterally movable tuyères forming part of the fuel supporting surface for a furnace or other combustion chamber, and has for an object to provide tuyères composed of independent and interchangeable, juxtaposed blocks presenting registering recesses which in combination produce apertures for tuyère openings for the eduction of air from the air ducts underlying the fire supporting structure.

With these and other objects, the invention comprises certain novel units, combinations and arrangements of parts and units as will be hereinafter more fully described and claimed.

Referring to the accompanying drawings, which are made a part hereof, and on which similar reference characters indicate similar parts,

Figure 1 is a vertical transverse sectional view through a plurality of tuyères of the rocking type,

Figure 2 is a view in elevation of a conventional means for actuating the laterally movable tuyères,

Figure 3 is a perspective view of one of the tuyère units of the rocking type, and

Figure 4 is a sectional view showing in elevation one of the tuyère units of the sliding type.

The laterally movable tuyère which forms the subject matter of this application may be embodied in a variety of specific structures provided only that a means is secured for producing lateral movement of the tuyère relative to the supporting members.

In Figure 1 a conventional furnace is indicated by the walls 10 and at Figure 2 by the front 10'. Within the furnace structure a plurality of supporting members 11 are

erected preferably, though not necessarily, 50 forming the upstanding edges of retorts 12 which retorts form no part of the present invention except so far as they may be properly spaced apart to support the tuyères.

Above the spaced supporting members, 55 shafts 13 are journaled, the supporting members being provided at their upper edges with curved bearing surfaces 14 struck upon an arc with the center of the shaft 13 60 as the center of curvature.

The tuyères which are mounted to rock in the curved bearing surfaces 14 are of any length that the exigencies of use may make desirable and are built up of units 15 having means for rigid engagement with the 65 shaft 13 as by constructing the shaft 13 square and providing the units 15 with squared openings 16. It is obvious that any

other equivalent means of attaching the units to the shaft may be substituted. As 70 many of the units 15 are employed, juxtaposed upon the shaft 13 as will unitedly produce the length of tuyère the fire-supporting surface makes necessary. Each of the units comprises a web 17 with ribs 18 about the 75 periphery forming recesses 19, the opposite sides of said blocks being substantially similar and the recesses registering whereby the registering recesses produce tuyère openings which are fed through the opening 20 80

with air from air ducts 21 underlying the tuyères. The lower surface of each tuyère unit is curved as at 22 to correspond to the curved bearing surface 14 of the collocating supporting members, the ribs 23 being in engagement with the similar ribs of the adjacent block so that the air passes from the air ducts 21 only upwardly through the opening 20 and is then divided to be discharged through the several tuyère openings into the 90 fuel mass between and covering the tuyères.

Any approved and convenient means may be employed for rocking the tuyères. A conventional means is here shown consisting of a lever 24 pivoted at 25 having a walking beam 26. Links 27 and 28 connect to opposite ends of the walking beam 26 while other links 29 and 30 unite the arms 31 of

the shafts 13 into pairs, rocking simultaneously in opposite directions. In Figure 2 arrows are employed to indicate the movement of the lever 24 both ways from normal, 5 while at Figure 1 dotted lines are employed to show the movement of the tuyères to their limit in one direction, while broken lines are employed to show the movement of the tuyères to their limit in the opposite direction.

Instead of having the tuyère rock, structure may be employed as shown at Figure 4 wherein the blocks slide upon the flanges of the supporting structures 11'. The units 32 15 as shown at Figure 4 which, combined as hereinbefore described, make up the complete tuyère, are mounted to slide upon the flanges 33 of the supporting members 11', undercuts 34 being provided to accommodate 20 the flanges. The shaft 13' differs from the shaft 13 in that lugs or ribs 35 are provided engaging notches 36 in the undersides of the units 32 whereby such units are moved with the oscillation of the lug or rib 35. It is 25 obvious that in this type the member 35 may extend throughout the entire length of the shaft 13' and simultaneously slide all of the blocks laterally or may engage alternate or other portions of the blocks moving such 30 blocks only, the intermediate blocks remaining stationary. It is immaterial to the present invention whether all of such blocks move or whether some move and others are stationary, the result attained being substantially equivalent to that of moving the tuyère members laterally for the purpose of breaking up and agitating the coked mass.

With the employment of either type of laterally movable tuyère the lateral movements 40 may occur at such times and intervals as the exigencies of ignition may make necessary or desirable, and if found desirable mechanical and automatic means may be employed for the purpose of moving the tuyères, but 45 such moving means, forming no part of the present invention, is only suggested as a mechanical equivalent for the manual means disclosed by the lever 24 and is not intended to enlarge or restrict the scope of the invention.

Having thus described my said invention, what I claim as new and desire to secure by Letters Patent, is:

1. A fire supporting structure comprising 55 a plurality of pairs of supporting members having curved surfaces, a tuyère supported for rocking movement on the curved surfaces of each pair and each tuyère having inlet and outlet passages for air, substantially as 60 set forth.

2. A fire supporting structure comprising 65 a plurality of pairs of supporting members having opposed curved surfaces struck from the same center, a tuyère supported on each 70 pair of opposed surfaces, and each tuyère

having an air inlet below and air outlets at its opposite sides, substantially as set forth.

3. A fire supporting structure comprising a pair of spaced supporting members forming a section of the upper wall of an air 70 duct, a tuyère resting on said surfaces and having an opening in its lower part to communicate with the air duct and symmetrically placed outlet openings in its opposite sides, substantially as set forth.

4. A fire supporting structure comprising a pair of spaced supporting members forming a section of the upper wall of an air duct, a tuyère resting on said surfaces and having an opening in its lower part to communicate with the air duct and the upper portion having equal arcuate sides with outlet openings therein, substantially as set forth.

5. A fire-supporting structure comprising 85 supporting members spaced apart to form an air duct therebetween, a tuyère mounted upon the upper spaced edges of the supporting members and spanning the air duct and composed of a plurality of blocks juxtaposed, each of said blocks being provided with recesses forming with the adjacent block laterally directed tuyère openings in communication with the air duct, and means to move the blocks laterally relative to the 90 supporting structure.

6. A fire-supporting structure comprising a plurality of supporting members spaced apart to form an air duct therebetween, a tuyère supported upon the upper spaced edges of the supporting members and composed of a plurality of juxtaposed blocks, each of said blocks comprising a web and spaced ribs forming recesses between the ribs registering with like recesses in the adjacent block such combined recesses forming laterally directed tuyère openings in connection with the air duct, and means to move the blocks laterally.

7. A tuyère composed of a plurality of 110 blocks each of said blocks having an arcuate bearing surface and ribs forming laterally directed recesses, and with means for engaging a collocating member.

8. A tuyère comprising a plurality of 115 blocks having arcuate bearing surfaces, each of said blocks provided with laterally extending ribs forming laterally directed tuyère openings and a shaft extending through and uniting the several blocks and 120 disposed with its center as the center of curvature of the arcuate bearing surface.

9. A tuyère provided upon its underside with a bearing surface and upon its lateral faces with ribs forming recesses therebetween and with means for engaging a collocating member.

10. A tuyère block comprising a web having ribs outstanding from its opposite faces forming recesses therebetween, some of said 130

recesses being outlet recesses and others of said recesses being inlet recesses, and means to engage upon a collocating member.

11. An ovoid-shaped tuyère block provided upon its arc of larger radius with a bearing surface and about its other arcuate peripheral surfaces with members forming therebetween tuyère openings.

In witness whereof, I have hereunto set my hand and seal at Philadelphia, Pa., this 10 twenty-sixth day of January, A. D. nineteen hundred and twenty.

JOSEPH H. ROACH. [L. S.]
